CONVERTER FOR TELEGRAPHIC SIGNAL

Francis J. Biltz, Glen Lake, Minn., and Herbert G. Nilles, Jr., Grand Rapids, Mich., assignors, by mesne assignments, to the United States of America as represented by the Secretary of the Navy

Application June 28, 1954, Serial No. 439,948

8 Claims. (Cl. 178—70)

This invention relates to conversion apparatus and more particularly to apparatus for converting a transmitted signal originally containing intelligence into a train of pulses which represent the intelligence originally transmitted.

For many years intelligence has been transmitted from one point to distant points in the form of pulses of energy, electrical, sound, etc., which pulses convey the desired intelligence by their presence or absence. The original telegraphic codes comprised energy pulses of more than one width or duration but modern automatic telegraphic equipment such as the teletypewriter operate in response to energy pulses of uniform width. The intervals between energy pulses are also maintained constant, and intelligence is conveyed by the relative positions of the pulses and separating intervals. Thus, a common code for the transmission of intelligence by teletypewriter equipment comprises five equal time periods, each of which periods may or may not contain an energy pulse in accordance with the information transmitted.

The transmission of intelligence by such codes over short distances may be by wires, and the pulses may be in the form of direct current pulses of one or both polarities. For long range transmission, however, the pulses usually comprise an audio frequency alternating current called a tone. The tone source is keyed in the desired sequence to produce the tone pulses in the desired form for conveying the intended intelligence, and the resulting train of pulses may be then used to modulate a high frequency carrier for radio broadcasting or may be transmitted directly over wires. In either case, the transmitted signal may be subjected to interference such as by electrical storms or electrical surges on transmission lines resulting in short duration hiatuses in the tone pulses and short duration noise pulses in the intervals separating the tone pulses. The net result is an undesired multiplication of pulses which often produces garbling of the intelligence by the receiving equipment. A converter for converting the distorted signal into a signal which can be properly utilized by the receiving equipment is necessary.

It is, therefore, an object of this invention to provide apparatus for converting a distorted signal containing intelligence into a series of undistorted pulses.

Another object of this invention is to provide a novel and improved apparatus for converting distorted alternating tone pulses separated by characteristic intervals into direct current pulses and intervals of undistorted character.

A further object of this invention is to provide apparatus for reconstructing a train of direct current pulses containing intelligence from a distorted alternating current signal of pulses.

Other objects and advantages of the invention will hereinafter become more fully apparent from the following description of the annexed drawings, which illustrate a preferred embodiment, and wherein:

2

The single figure of the drawing is a block diagram of the apparatus of this invention.

Structure

Referring now to the drawing, the reference numeral 5 designates a teletypewriter or other communication equipment which generates electrical signals representative of intelligence to be transmitted to a distant station. The output of the teletypewriter 5 is connected to the input of a transmitter 7 in which the direct current pulses from teletypewriter 5 are converted into pulses of an audio frequency tone and are then used to modulate a radio frequency carrier for broadcasting through space.

A receiver 9 picks up the broadcast signals from the transmitter 7 and detects them to eliminate the radio frequency carrier. The output of the receiver 9 is connected to the input of an amplifier 11. The amplified signal output of the amplifier 11 is then applied to a rectifier and filter circuit 13, and the output of the circuit 13 is coupled to a keyed relaxation oscillator 15 which produces rectangular pulses, all of which are of the same amplitude and polarity, from individual keying pulses from the circuit 13. The output of the relaxation oscillator 15 is applied to an integrating circuit 17 which integrates the pulses produced by the relaxation oscillator 15 into a series of saw-tooth waves and applies the resulting signal in parallel to two transmission channels, a mark channel and a space channel.

The mark channel comprises a limiter 19 controlling the firing of a thyratron 21 which forms an electronic switch, an integrator 23 for integrating the pulse output of the thyratron 21, and a limiter 25 connected to the output of the integrator 23 and controlling the firing of a thyratron 27.

The space channel comprises a differentiating circuit 31 which differentiates the saw-tooth waves from the integrator 17. The differentiator 31 feeds an integrator 33, the output of which is connected to the input of a limiter 35, which controls the conduction of a thyratron 37 which forms an electronic switch. An integrator 39 is connected to the output of the thyratron 37 and integrates the output therefrom, feeding its output into a limiter 41 which controls the firing of a thyratron 43.

A double-pole, double-throw switch 51 comprising terminals 51a, 51b, 51c, and 51d and switch arms 51e and 51f is connected to the output of the thyratron 27 by terminals 51a and 51c and to the output of the thyratron 43 by terminals 51b and 51d. Since the outputs of the thyratrons 27 and 43 are the outputs of the mark and space channels respectively, both channels are connected to the switch 51. The switch arm 51e is connected to the input of an integrator 53 which integrates the pulse output from the mark or space channels and applies its integrated output to a limiter 55.

A double-pole, double-throw switch 57 comprising terminals 57a, 57b, 57c, and 57d and switch arms 57e and 57f is connected to the limiter 55 by terminals 57a and 57c and to the switch arm 51f by terminals 57b and 57d. The switch arms 57e and 57f are connected to the inputs of thyratrons 61 and 59 respectively. The outputs of the converter are taken from the thyratrons 59 or 61.

The threshold limiters 19, 35, 25, 41 and 55 have their limiting thresholds controlled by appropriate biasing means. In the apparatus illustrated, the limiters 19 and 35 are both connected to a common source of negative bias voltage (not shown) by a potentiometer 18 having a wiper arm 34. The threshold of the limiters 19 and 35 may be varied by moving the wiper arm 34 along the potentiometer 18. The limiters 25 and 41 are similarly controlled by the positioning of a wiper arm 40 along a potentiometer 24, and the limiter 55 is controlled by a potentiometer 54 having a wiper arm 56. It is to be

understood that each of the limiters 19, 35, 25, 41 and 55 may be independently biased.

The thyratrons of each pair of thyratrons 21 and 37, 27 and 43, and 59 and 61 are interconnected so that the initiation of conduction through one thyatron of a pair terminates the conduction through the other of the pair. Whenever the apparatus is energized, one thyatron of each pair is conducting. Such circuitry is old and not part of this invention and will not, therefore, be described herein in greater detail.

Operation

The waveform of the signal output of each stage is illustrated adjacent the output of its respective stage, and the part of the apparatus wherein any particular waveform is found is indicated by appropriate arrows.

The output from the teletypewriter 5 is a train of direct current pulses which are of a duration predetermined by the machine and are separated by characteristic intervals of no-energy. The particular arrangement, the presence or the absence, of the pulses conveys the intelligence which is to be transmitted. For the purpose of this description, two adjacent time periods have been chosen to explain the operation of the apparatus. The waveform of the signal output from the teletypewriter 5 is shown as a first time period which contains a direct current pulse and a second time period which contains no energy. Time is considered as increasing from left to right. The beginning and end of each period is indicated by an index mark at the base line.

For transmission of the signal by radio broadcasting, the output of the teletypewriter 5 is applied to the input of the radio transmitter 7 wherein the direct current pulse is converted to a tone pulse, and the tone pulse modulates a radio frequency carrier wave. The modulated carrier is radiated from the transmitter antenna and is picked up by the antenna of the receiver 9 which detects the signal and eliminates the carrier wave. However, the signal transmitted from the transmitter 7 has been distorted in its transmission through space and, as is shown on the drawing, now contains a short duration hiatus in the pulse and short duration noise pulses in the period in which there was no pulse.

The amplifier 11 amplifies the detected signal from the receiver 9 and applies it to the rectifier and filter 13. The rectifier and filter 13 convert the alternating tone pulse into a varying direct pulse and filter out some of the higher frequency components. The rectified and filtered signal is then applied to key the relaxation oscillator 15 which produces a series of pulses, all of which have the same amplitude and polarity; each pulse from the rectifier and filter 13 keying the oscillator 15 to produce one pulse therefrom. The integrator 17 receives the series of pulses from the oscillator 15 and integrates the pulses into a series of saw-tooth waves, the amplitudes of which vary directly with the duration of the respective pulses which produced them. Although the integrator 17 may be of any suitable type, a capacitor type is preferred, wherein the pulse is applied to a capacitor circuit having a long time constant. The voltage across the capacitor then increases gradually for the duration of pulse being integrated. If the capacitor is discharged through a short time constant circuit after the pulse has decayed, the voltage across the capacitor drops sharply, producing the saw-tooth wave illustrated.

The saw-tooth output of the integrator 17 is applied to the mark and space channels in parallel, and the mark channel will be described first. The threshold limiter 19 is so biased that it conducts only when the applied input signal reaches or exceeds a predetermined amplitude. This predetermined amplitude is represented by the dashed line which crosses the saw-tooth wave from the integrator 17. Therefore, the limiter 19 conducts in response to only the two larger saw-tooth waves illustrated. These waves represent the two portions of the original

tone pulse which was divided in two by interference. The output of the limiter 19 then comprises two rectangular pulses; one comparatively wide and the other narrow; in the first time period. When these two pulses are applied to the thyatron 21, they initiate conduction through the thyatron 21 which conducts until it is cut-off by conduction through the thyatron 37.

In the meantime, the saw-tooth waves from the integrator 17 were also applied to the space channel and differentiated by the differentiator 31. The output of the differentiator 31 comprises a series of sharp pulses of varying durations and amplitudes; the duration and amplitude of each pulse depending upon the amplitude and discharge time of the pulse from which it was formed. Since the differentiator produces a sharp pulse for each rapid change in the amplitude of the applied signal, the sharp pulses are produced by the decay of the saw-tooth waves from the integrator 17, and the greater the rate of change of the saw-tooth, the higher and wider the differential pulse will be. The differential pulses from the differentiator 31 are applied to the input of the integrator 33 which produces a saw-tooth wave for each pulse applied thereto. The train of saw-tooth waves from the integrator 33 is not the same as the train of saw-tooth waves from the integrator 17. Since the pulse from the differentiator 31, which pulse is one from which the saw-tooth waves from the integrator 33 are formed, is the result of the trailing edge of the saw-tooth wave from the integrator 17, the leading edge of the saw-tooth wave from the integrator 33 occurs at the same time as the trailing edge of the saw-tooth wave from the integrator 17.

The saw-tooth waves from the integrator 33 are applied to the input of the limiter 35 which responds to that portion of the saw-tooth which is above the dashed line. Conduction through the limiter 35 produces a pulse which triggers the thyatron 37 and cuts-off the thyatron 21. Since the pulse which triggers the thyatron 37 is formed after the pulse which triggers the thyatron 21 has decayed, when the thyatron 37 is triggered, the thyatron 21 has been conducting for a period of time.

For this discussion, it is assumed that the thyatrons 37 and 43 have been conducting due to triggering by preceding cycles. When the first pulse of the illustrated cycle is applied to the thyatron 21, that thyatron begins to conduct, cutting-off conduction through the thyatron 37 and producing a first output pulse. When the first pulse from the limiter 35 is applied to the thyatron 37, which pulse occurs at a later time than the first pulse from the limiter 19 as explained above, the thyatron 37 begins conducting, cutting-off conduction through the thyatron 21. The second pulse from the limiter 19 then triggers the thyatron 21 which fires and terminates conduction through the thyatron 37. The conduction through the thyatron 21 ceases when a succeeding pulse from the limiter 35 triggers the thyatron 37, and the thyatron 21 does not again begin to conduct or cut-off the thyatron 37 until the succeeding cycle. The output of the thyatron 21 comprises two complete pulses within the two periods illustrated and the output of the thyatron 37 comprises a final portion of a pulse at the beginning of the first time period, a short complete pulse in the first time period, and an initial portion of a pulse during the second time period.

The outputs of the thyatrons 21 and 37 are then applied to integrators 23 and 39 respectively where the saw-tooth waves are produced from the applied pulses. The limiters 25 and 41 are each adjusted to conduct only on those portions of the saw-tooth waves which are above the threshold voltage represented by the dashed lines on the drawings. The limiters 25 and 41 then produce only one output pulse each.

The outputs from the thyatrons 27 and 43 are each representative of the original signal pulse produced by the teletypewriter 5, but both are displaced in time due

to the operation of the apparatus. Since the limiters 19, 35, 25, and 41 respond to portions of the saw-tooth waves which occur later than the leading edges of these waves, the resulting output from the limiters is delayed in phase from the original signals which produced the output. The apparatus operates the same for all the cycles applied to it and each cycle will be delayed by the same amount so that the resulting reconstructed signal will be the same as the original signal except in phase. Since all the components, the pulses and the intervals, are present in the final signal in the same order and of the same duration as those in the original signal, no intelligence is lost by the delay. However, should time distortion or changes in the phasing of the signal be desired, the switches 51 and 57 and the integrator 53 and the limiter 55 are provided.

The outputs from the thyratrons 27 and 43 are applied to terminals 51a and 51d and to 51b and 51c respectively, and, depending on the positions of the switch arms 51e and 51f, either output may be applied to the integrator 53 and limiter 55. The relative durations and phasing of the pulses from the thyratrons 27 and 43 may be varied by changing the threshold of the limiter 55, thus controlling the time at which the thyratrons 59 or 61, whichever is connected to the limiter 55, fires and also the length of time during which it conducts. Since the time of initiation of conduction through that thyratron which is connected to the limiter 55 controls the time of termination of conduction through the other thyratron, if the firing of one thyratron is delayed, the pulse output from the other is lengthened. The arms 51e and 51f and the arms 57e and 57f are all mechanically ganged to be moved together to connect either the output of the mark or of the space channel through the integrator 53 and the limiter 55.

Since there will always be some point at which a received pulse ends, the differentiator 31 will always produce a sharp pulse which represents the end of the received pulse. This sharp pulse will serve to fire the thyratrons 37, 43 and 59 in the space channel and terminate conduction of the thyratrons 21, 27 and 61 in the mark channel. Therefore, the mark channel will produce an output pulse of approximately the desired duration and the space channel will produce pulses of the desired duration and representative of the intervals between the pulses of the mark channel. Since only one channel can produce a pulse output at any time, the pulses of the space channel determine the intervals of the mark channel. Thus, the two channels of the apparatus operate together to produce an undistorted signal which is the substantial duplicate of the original signal from the teletype writer 5.

The apparatus of this invention will operate to reconstruct a train of pulses of predetermined duration separated by characteristic intervals from a badly distorted signal, even though that signal be alternating. The reconstructed pulse train may safely be applied to modern printing or teletypewriter equipment without fear of garbling; saving time and accomplishing the primary mission of the equipment.

Obviously many modifications and variations of the present invention are possible in the light of the above teachings. It is therefore to be understood that within the scope of the appended claims the invention may be practiced otherwise than as specifically described.

What is claimed is:

1. Apparatus for converting a distorted signal which contains intelligence in the form of pulses of predetermined duration separated by characteristic intervals into a series of pulses all of which are of the same amplitude and polarity and of said predetermined duration and separated by said characteristic intervals, said signal having been distorted by interference therewith resulting in pulses in said intervals and hiatuses in said pulses; said apparatus comprising means for creating a series

of first saw-tooth waves from said distorted signal, each of said first saw-tooth waves being created from one of said pulses of said distorted signal and having a maximum amplitude which is directly dependent upon the amplitude and duration of said one signal pulse; a first transmission channel and a second transmission channel, said first saw-tooth waves being applied to said first and second channels in parallel; first electronic switch means in said first channel, said first electronic switch means being adapted to remain in the conductive or the non-conductive state until changed by external means; first initiating means in said first channel for initiating conduction through said first electronic switch means, said first initiating means being responsive to said first saw-tooth waves which exceed a predetermined amplitude; differentiation means in said second channel for differentiating said first saw-tooth waves into sharp pulses; integrating means in said second channel connected to said differentiation means for integrating said sharp pulses into second saw-tooth waves the amplitudes of which are directly dependent upon the amplitudes and durations of said sharp pulses; second electronic switch means in said second channel, said second electronic switch means being adapted to remain in the conductive or non-conductive state until changed by external means; second initiating means in said second channel for initiating conduction through said second electronic switch means, said second initiating means being responsive to said second saw-tooth waves which exceed a predetermined amplitude; 30 said first and second switch means being so interconnected that the initiation of conduction through one electronic switch means terminates conduction through the other electronic switch means.

2. The apparatus defined in claim 1 wherein said first and second initiating means comprise threshold limiters so biased as to conduct only when the amplitudes of the applied saw-tooth waves overcome the bias, said amplitudes for said first and second initiating means being greater than the maximum amplitude of the saw-tooth waves generated from said short duration pulses in said intervals and from the short duration hiatuses in said intelligence pulses, whereby said initiating means and said respective electronic switch means do not change their states in response to said respective short duration pulses or hiatuses.

3. Apparatus for reconstructing a train of direct current pulses of predetermined duration separated by precise characteristic time intervals from an alternating signal comprising tone pulses representative of said direct current pulses and periods of no-tone representative of said intervals, said signal having been distorted by interference in such a manner that said periods contain noise pulses and said tone pulses contain hiatuses; said apparatus comprising keyed oscillator means responsive to said alternating signal for generating a train of direct current pulses of like amplitude and polarity of said generated pulses being coincident in initial phase and duration with its keying pulse; first means connected to said oscillator means for integrating said generated pulse train into a series of first triangular waves related individually to the pulses of said pulse train, the amplitude of each of said first triangular waves being dependent upon the duration and amplitude of the generated pulse from which it is formed; a first transmission channel and a second transmission channel, said series of first triangular waves being coupled to said first and second channels in parallel; said first channel comprising first means for producing individual rectangular pulses in response to said first individual triangular waves which exceed a predetermined minimum amplitude, said first rectangular pulses being related in initial phase and duration to the amplitude of said respective first triangular waves from which they are formed; first thyratron means in said first channel connected to said first rectangular pulse producing means and responsive to said

first rectangular pulses to fire; said second channel comprising means for differentiating said series of first triangular waves into a series of sharp pulses; second means connected to said differentiating means for integrating said sharp pulses into a series of second triangular waves, the amplitude of said second triangular waves being dependent upon the amplitude and duration of the respective sharp pulses from which they are formed; second means responsive to said second individual triangular waves which exceed a predetermined minimum amplitude for producing second individual rectangular waves related in initial phase and duration to the amplitudes of the respective second triangular waves from which they are formed; and second thyratron means connected to said second rectangular wave producing means and responsive to said individual rectangular waves to fire; said first and second thyratron means being so interconnected that the firing of one thyratron means terminates conduction through the other thyratron means.

4. The apparatus defined in claim 3 wherein said first and second rectangular wave producing means comprise threshold limiters so biased as to conduct only when the amplitudes of the applied triangular waves overcome the respective biases, said amplitudes for producing conduction through said first and second rectangular pulse producing means being greater than the maximum amplitudes of the triangular waves generated by said hiatuses in said tone and by said noise pulses in said intervals, whereby said respective thyratron means do not fire in response to said respective short duration noise pulses or hiatuses.

5. Apparatus for converting an alternating signal into a train of direct current pulses representing intelligence, said alternating signal comprising tone pulses of predetermined duration separated by precise intervals, said signal being distorted by interference which produces hiatuses in said tone pulses and sharp pulses in said intervals; said apparatus comprising means for receiving said alternating signal; means connected to said receiving means for converting said alternating signal into a train of first pulses all of which are of the same amplitude and polarity, first pulses being produced for each said noise and intelligence pulse; first means for integrating said first pulses into a series of first saw-tooth waves having maximum amplitudes which are directly dependent upon the durations of the respective first pulses from which they are formed; a first channel and a second channel; means for applying said first saw-tooth waves to said first and second channels in parallel; said first channel comprising a first threshold limiter biased to conduct only on the peaks of said first saw-tooth waves which exceed a predetermined amplitude; and a first thyratron connected to said first limiter, conduction through said first limiter initiating conduction through said first thyratron; said second channel comprising a differentiation circuit for differentiating said first saw-tooth waves into respective sharp pulses; a second means connected to said differentiation circuit for integrating said sharp pulses into a series of second saw-tooth waves having peak amplitudes which are directly dependent

upon the durations and amplitudes of the respective first pulses from which they are formed; a second threshold limiter biased to conduct only on the peaks of said second saw-tooth waves which exceed a predetermined amplitude; and a second thyratron connected to said second limiter, conduction through said second limiter initiating conduction through said second thyratron, said first and second thyratrons being so interconnected that initiation of conduction through one terminates conduction through the other.

6. The apparatus defined in claim 5 further including a third integrating means connected to said first thyratron; a third threshold limiter connected to said third integrating means; and a third thyratron connected to said third limiter, the functions of said third integrating means, third limiter and third thyratron being the same as the functions of said first integrating means, first limiter and first thyratron.

7. The apparatus defined in claim 6 further including a fourth integrating means connected to said second thyratron; a fourth threshold limiter connected to said fourth integrating means; and a fourth thyratron connected to said fourth limiter, said fourth integrating means, fourth limiter and fourth thyratron functioning the same as said second integrating means, second limiter and second thyratron.

8. The apparatus defined in claim 7 further including a first double-pole double-throw switch comprising a first pair of switch arms and first and second pairs of switch terminals, the output of said third thyratron being connected to said first pair of switch terminals in parallel, said fourth thyratron being connected to said second pair of switch terminals in parallel, said first pair of switch arms contacting one pair of said first or second pairs of switch terminals at any time, a fifth integrating means, a fifth threshold limiter connected to said fifth integrating means, one of said first pair of switch arms being connected to the input to said fifth integrating means, a second double-pole double-throw switch comprising a second pair of switch arms and third and fourth pairs of switch terminals, the other of said first pair of switch arms being connected to said fourth pair of switch terminals, the output of said fifth limiter being connected to said third pair of switch terminals, fifth and sixth thytratrons, the input of said fifth thyratron being connected to one of said second pair of switch arms and the input to said sixth thyratron being connected to the other of said second pair of switch arms, said first and second pair of switch arms being operatively ganged together.
